US0D1113444S

(12) **United States Design Patent** (10) **Patent No.:** **US D1,113,444 S**
(45) **Date of Patent:** **** Feb. 17, 2026**

(54) **POD**

(71) Applicant: **The Cumulus Coffee Company**, New York, NY (US)

(72) Inventors: **Gordon D. Row**, Groton, MA (US); **Demetrio D. Anaya**, Somerville, MA (US); **Adam Michael Paskow**, New York, NY (US); **Nathan J. Tyrowicz-Cohen**, Arlington, MA (US); **Zachary H. Zieper**, Woburn, MA (US); **Mesh Gelman**, New York, NY (US)

(73) Assignee: **The Cumulus Coffee Company**, New York, NY (US)

(**) Term: **15 Years**

(21) Appl. No.: **29/971,096**

(22) Filed: **Oct. 31, 2024**

Related U.S. Application Data

(63) Continuation of application No. 29/942,287, filed on May 14, 2024.

(51) **LOC (15) Cl.** **07-06**

(52) **U.S. Cl.**

(57) **CLAIM**

The ornamental design for a POD, as shown and described.

DESCRIPTION

FIG. 1 is a front perspective view of a POD showing our new design;

FIG. 2 is a bottom perspective view thereof;

FIG. 3 is a side elevational view thereof;

FIG. 4 is a top elevational view thereof; and,

FIG. 5 is a bottom elevational view thereof.

In the drawings, the broken lines illustrate portions of the POD that form no part of the claimed design.

1 Claim, 5 Drawing Sheets
